CHAIN CROWD SHOVEL EXCAVATOR

Erich H. Lichtenberg, Emil L. Tranaas, and
 William F. Steffen, Milwaukee, Wis., as-
 signors to Koehring Company, Milwaukee,
 Wis., a corporation

Application February 13, 1935, Serial No. 6,372

6 Claims. (Cl. 214—135)

The present invention appertains to what are commonly known to those versed in the art as shovel excavators or excavating machines. Such machines comprise generally a traction base, a body or cab structure mounted thereon containing the driving or operating machinery, a boom and means for raising and lowering the boom, and a shovel dipper connected by a dipper stick or handle with the boom. The operating machinery used for the operations of thrusting out or crowding the dipper to its work, and retracting or racking in the dipper, so called, are controlled from the operating machinery either by cable drives, chain drives, or shaft and gear drives.

Since the boom is a pivoted boom to permit of its raising and lowering actions, the transmission devices for conveying the driving forces of the operating machinery to the dipper stick or handle must be designed to communicate said forces in some way through the supporting means for the boom, past the chute of the boom, and up to a point intermediate the ends of the boom where the dipper stick or handle has shiftable or sliding connection with the boom for actuating purposes.

The present invention contemplates a novel chain drive for transmitting forces from the operating drum mechanism on the body of the machine to the dipper stick for crowding out and retracting the latter with its dipper.

Chain drive means for the purpose stated have been proposed heretofore, as exemplified for instance in the patent of Hanson, No. 1,808,409, issued June 2, 1931, wherein one drive chain connected with the reversing drum mechanism is connected to a transmission shaft at the axis of the boom and a second drive chain carries off the drive from said shaft to the dipper stick, being directly connected to the shipper shaft on the boom.

The aim of the present invention has been to design a single chain drive for the purpose stated, and this has required the employment of novel means for guiding the chain, or flexible member equivalent thereto, as it passes from the operating drum mechanism to the foot of the boom, thence to the shipper connection with the dipper stick or handle, and back from the last connection past the foot of the boom again to the drum mechanism. The problem involved lies in the fact that the boom is required to be raised and lowered in the various operations of the shovel dipper. Obviously, the raising and lowering of the boom varies the positions of the upper and lower runs or loops of the chain when a single

chain is trained downwardly from the drum mechanism of the shovel body around devices at the foot of the boom and upwardly to the intermediate portion of the boom where connection of the chain for driving action with respect to the dipper stick or handle is made.

The present invention contemplates provisions such that during the elevating or lowering adjustments of the boom, guide members associated with the boom, and its support adjacent to the foot portion of the latter, operate to maintain a substantially uniform tension upon the driving chain or flexible member, so that no undue looseness interfering with the proper operation of said chain will be incurred, notwithstanding that the boom may be adjusted to any position between its upper limit and lower limits of working movement.

The invention involves a unique mounting of the said guide means which comprise upper and lower sprocket gears engaging the upper and lower bights or loops of the chain, respectively, which mounting involves a supporting of the guide member for the lower loop below the axis of the boom and a supporting of the guide member for the upper loop above the said axis at a substantially greater distance therefrom than is the point of support of the lower member. The peculiar mounting means just referred to involves the peculiar location of the guide member axes at opposite sides of the boom pivotal axis, which location has been determined empirically but involves definite principles as to the arrangement of the guide members and mode of training the driving chain thereover in such a way that the looseness of the upper loop or bight of the chain, tending to be created by the action of lowering the boom to elongate or cause the upper and lower sides of the chain to approach alignment, will be taken up by the moving adjustment of the upper guide member relatively to the lower member and relatively to the axis of the boom, thereby to maintain the chain under a substantially uniform tension under all conditions of adjustment of the boom in its working range of movement upwardly and downwardly.

Certain preferred embodiments of the invention are illustrated in the accompanying drawings, but I do not wish to be limited thereto since a modification of the specific constructions provided may be employed.

In the accompanying drawings—

Figure 1 illustrates a side elevational view of a shovel excavator or shovel crane embodying the invention, dotted lines illustrating the dipper and dipper handle in upraised position fully extended,

and full lines showing the same in lower digging position fully extended.

Figure 2 is a fragmentary diagrammatic view illustrating primarily the locations of the drum mechanism for driving the chain or flexible actuating device, and the relative locations of the guide members or idler sprocket gears, the pivotal axis of the boom, and the disposition of the upper and lower loops of the drive chain when the boom is at different adjustments in its working range upwardly and downwardly.

Figure 3 is a fragmentary plan view showing more clearly the method of mounting the guide members or sprockets upon the foot of the boom.

Figure 4 is a side elevation of the parts illustrated in Figure 3, the body of the boom partially broken away.

Figure 5 is a sectional view of the mountings of the upper guide member.

Figure 6 is a fragmentary view showing a modified form of the invention wherein the driving chain, instead of being endless as in Figure 1, has ends directly attached to the dipper stick.

The shovel excavator or crane construction as depicted in Figure 1 of the drawings is very largely of the conventional type. It comprises the so-called swing body A adapted to rotate upon a turntable B supported upon endless traction belts C diagrammatically shown. At one end of the swing body A is the boom D adapted to be raised and lowered by a hoisting cable means including the cable E. On the boom D is supported the dipper stick or handle 1 equipped at its outer end with the dipper 2 and adapted to be crowded out, and retracted, after the manner of ordinary implements of this character. The boom D is pivoted to the swing body A at the axis 3, see Figures 1 and 3. The dipper stick 1 is equipped with the usual racks 4 on the side members of said dipper stick, with which engage the shipper pinions 5 fixed to a shipper shaft 6 to which movement is imparted by a drive chain 7, the mounting of which is the primary feature of the present invention. The shipper shaft 6 carries a sprocket gear 8 about which the chain 7, which is preferably a sprocket chain, passes and is inter-engaged therewith.

As customary in machines of the type of the invention, the driving mechanism on the swing body A includes a reversible operating drum 9, on which is carried an operating sprocket gear 10 about which the chain 7 also passes and with which it is inter-engaged.

We now come to the peculiar feature of the invention, which lies in the mounting of the chain 7 in relation to the guiding means therefor located at the foot of the boom. This guiding means includes an upper idler sprocket gear 11 and a lower idler sprocket gear 12. The mounting of these sprocket gears 11 and 12 is peculiar the lower gear 12 being supported about an axis member or shaft 13 which is located in fixed position, said axis member 13 being supported by offsetting brackets 14 having the bearings 15 to receive said shaft 13. It is notable that the axis of the shaft 13 is located a short distance below the axis 3 for the boom.

The upper sprocket gear 11 may be mounted adjustably by having its supporting shaft 16 carried in adjustable bearings 17 shiftable in a plane somewhat transverse to the axis of the boom D by means of the adjusting screw devices 18 and the lock nuts 19 threaded thereon. Screws 18 pass through openings in the boom foot member 20 and are held against longitudinal displace-

ment by means of other nuts 21. The detail construction of the screws and their adjusting means is immaterial because any suitable means of this type for adjusting the bearing members 17 might be availed of. The bearing members 17 slide in suitable guides formed in the boom foot casting or member 20 previously referred to. The sprocket gear 11 is spaced a substantial distance from the gear 12.

It will be observed, of course, that the axis shaft 16 of the gear 11 is mounted at the opposite side of the axis 3 for the boom D from that at which the axis shaft 18 of the gear 12 is largely disposed.

In reference to the mode of training the chain 7 around the gears 11 and 12, it is notable that the upper bight or loop of the chain passes beneath and is inter-engaged with the gear 11, and the lower bight or loop of the chain 7 passes underneath and is inter-engaged with the gear 12. The space between the gears 11 and 12 must be sufficient that under any conditions of adjustment of the boom D upwardly and downwardly within its working range of utility, the upper loop or bight of the chain 7 will not engage with the teeth of the sprocket gear 12, or preferably should not.

In general disposition the sides or bights of the chain 7 may be said to extend at an angle from a medial point, providing what is characterized herein as an upper loop or bight and the lower loop or bight, both together having an L-shaped arrangement when the boom D is at and near the upper limit of its working adjustment. When the boom D is lowered by operation of the boom hoisting cable E, the tendency of the angularly extending portions of the chain 7 is to move toward alignment. Even when the boom D is at its lower limit of movement, however, alignment of the angularly extending portion of the chain 7 is not achieved.

It will be apparent that by reason of the arrangement of the upper and lower loops or bights of the chain 7 when the boom D is raised from the position shown in Figure 1, the tendency of the upper bight will ordinarily be to assume a looseness, while the lower bight or loop will become tight. However, the said upper bight or loop of chain 7 under the above conditions is acted upon by a shifting of the sprocket gear 11 counterclockwise backwardly about the axis of the boom 3 incident to the raising of said boom whilst there is a slight shifting of the sprocket gear 12 counterclockwise forwardly in reference to said axis 3 at the same time. By reason of the location of the axis members 16 and 13 at properly determined distances eccentric to the axis 3 of the boom, in such a manner that distance a is equal to the distance b (Fig. 2), the shifting of the sprocket gears 11 and 12 relatively to the axis 3 and to the portions of the chain 7 with which they engage maintains the chain bights or loops substantially under the same tension at all times, and thus looseness is not permitted to disturb such tension.

The only purpose in providing the adjusting means 16, 17, 18, 19, 20, 21 is to take up wear on the chain as its life continues, there always being a certain amount of such wear by reason of the heavy work which chain of this kind performs in an excavating implement for the purposes mentioned.

In Figure 2 there is illustrated diagrammatically a reversible driving member 9 and a portion of the chain or flexible driving element 7 as trained

under the gears 11 and 12. Also, this figure shows the degree of shifting of the axis of the gear 12 on a rearward and upward arc generated about the pivot point of the boom, said arc disposed eccentrically below said pivot point. Likewise there is illustrated the range of movement of the upper gear 11 on an arc generated about the pivot point of the boom as the center, but located substantially a greater distance from the pivot point than the arc in which the axis of the lower gear 12 moves. It has been determined that the arrangement of the axes of the parts D, 11, and 12, as illustrated in the drawings and described above, is such that a substantially uniform tension will be maintained upon the flexible driving member 7 at all positions of the boom D within the ordinary working range of elevation of said boom. The degree of efficiency of this member 7, with its substantially uniform tension maintained in the manner described, will be evident when it is stated that in ordinary practice in conjunction with a 1 1/4 yard excavating shovel of the type illustrated in the drawings, a looseness of $1/8$ " only is created in the chain 7 when the boom D is lowered to its maximum extent. This amount of looseness does not under practical conditions become at all objectionable from an engineering and practical standpoint, for obvious reasons.

In the construction of the invention in Figure 6, instead of using an endless chain as in the Figure 1 illustration, the upper ends of the flexible member or chain 7a are trained about two pulleys or guiding sprockets 22 and 23 carried by the boom and directly attached to the dipper stick. The upper loop or bight of the chain 7a is secured permanently by suitable fastening means to the upper end portion of the dipper stick 1 as shown at 24, while the outer end of the lower bight or loop of the chain 7a is attached at 25 to the lower end of the dipper stick adjacent to the point where it supports the dipper 2. At such lower end 25 a suitable adjusting device may be availed of to perform the function of the adjusting means 16, 17, 18, namely, to take up such looseness as may be created in the chain or member 7a incident to wear only. So far as the function of the parts 11 and 12 is concerned, this function, in reference to maintaining the member 7 or 7a under tension, is equally existent when the driving chain for the dipper takes the form of the endless construction of Figure 1, or takes the form of the arrangement in Figure 6.

The construction of the invention as set forth in the above permits that all the machinery necessary for the shovel attachment is mounted on the shovel boom and is therefore a part of the attachment, which, in commercial use is quite an advantage in that it is not necessary to mount extra machinery and parts on the swing body A. In other words, when the base of the machine, the swing body and traction devices, is equipped with a crane boom, it may easily be converted into a shovel by detaching the crane boom and replacing the same by a shovel attachment, as the only additional part that would go on the swing body A is the sprocket gear 10.

It will be seen therefore from the above explanation of the operation referred to herein, that the pivot points 16 and 13 of the sprocket gears 11 and 12 are arranged in such relation to the boom pivot 3 that the distances *a* and *b* between the center line or neutral axis *a'* (Figure 2) and the loops of chain 7 are equal, while

the distance between pivots 16 and 13 remains also equal under all conditions of operation.

The position of the gears 11 and 12 with respect to the boom pivot 3 is such that the lowest points of the pitch lines of said gears are at substantially equal distances from the horizontal axis of the boom pivot.

Having thus described our invention, what we claim as new and desire to secure by Letters Patent of the United States, is—

1. In an excavating shovel of the type described, comprising a body, a boom pivoted to the body, hoisting means for raising and lowering the boom, a dipper stick on the boom, driving mechanism on the body for the actuation of the dipper stick to crowd out and retract the same, including reversible means for such purpose, in combination with a single flexible member connected with said reversible means of the driving mechanism and leading past the foot of the boom and operatively connected for actuating the dipper stick, guide means on the foot of the boom and comprising spaced guide elements, under one of which an upper loop portion of the flexible member is trained, and under the other of which a lower loop portion of the flexible member is trained, the axis of the upper guide element being disposed at one side of the pivotal axis of the boom and the axis of the lower guide element being disposed at the opposite side of the pivotal axis of the boom, the positions of the axes of the guide elements being such that the distances between the upper loop portion and the neutral axis through the boom pivot, and between the lower loop portion and said neutral axis, are maintained substantially equal at all positions of working operation of the boom to thereby maintain a substantially uniform tension in the flexible member.

2. In an excavating shovel of the type described, comprising a body, a boom pivoted to the body, hoisting means for raising and lowering the boom, a dipper stick on the boom, driving mechanism on the body for the actuation of the dipper stick to crowd out and retract the same, including reversible means for such purpose, in combination with a drive chain operatively connected with the reversible driving means of the said driving mechanism, spaced parts of said drive chain being formed in upper and lower loops extending downwardly from the reversible driving means to the foot of the boom and thence upwardly along the boom to points of operative connection with the dipper stick for actuation of the latter, guide means for the upper and lower loops of said driving chain to maintain the same under a substantially uniform tension at all positions of adjustment of the boom upwardly and downwardly, in its ordinary working range, said guiding means including an upper sprocket above the pivotal axis of the boom and beneath which the upper loop or chain passes, and a lower sprocket beneath which the lower loop or chain passes and having its axis located beneath the pivotal axis of the boom, and means for adjusting the position of at least one of said sprockets so as to normally equalize the distances between the upper loop of the chain and the neutral axis through the boom pivot, and between the lower loop of the chain and said neutral axis, and thereby afford a substantially uniform tension in the chain in all working positions of the boom.

3. In an excavating shovel comprising a body having operating mechanism including a reversible driving member, a boom pivoted to the body, 75

- and a dipper stick on said boom movable for crowding out and retracting movements, hoisting means for raising and lowering the boom, and a driving connection between said driving member 5 and the dipper stick comprising a chain looped about and interengaged with the driving member of said operating mechanism and passing downwardly therefrom past the foot of the boom and thence upwardly to the dipper stick point of connection thereof in the form of upper and lower loops or side elements of the chain, and guide means on the foot portion of the boom including an upper sprocket beneath which the upper loop of the chain passes, and a lower sprocket beneath 10 which the lower loop of the chain passes, the axes of the said sprockets being located eccentric to the pivotal axis of the boom and at opposite sides of said axis, and the lower sprocket being relatively close to the pivotal axis of the boom and 15 the upper sprocket being a substantially greater distance away from the pivotal axis of the boom than the lower sprocket.
4. In an excavator shovel comprising a body, operating mechanism thereon including a reversible driving sprocket gear, a boom pivoted at its 20 foot to the body, a dipper stick on the boom, and a driving chain for crowding out and retracting the dipper stick by connection therewith, said driving chain being looped about the said driving sprocket gear and passing downwardly in upper 25 and lower portions to the foot of the boom and then passing upwardly to a point intermediate the ends of the boom where said looped portions are connected to actuate the dipper stick, and means 30 for maintaining the loops of the chain under a substantially uniform tension irrespective of the up and down adjustment of the boom about its pivotal axis, and comprising guide sprocket gears located at opposite sides of the pivotal axis of the boom, one guide sprocket gear being arranged 35 so that the upper loop of the chain passes beneath the same, and the other guide sprocket gear being disposed so that the lower loop of the chain passes beneath it, the guide sprocket gear 40 which engages the upper loop of the chain being located a distance from the pivotal axis of the boom many times the distance between the axis of the other guide sprocket gear and said pivotal 45 axis of the boom, whereby the action of raising

and lowering the boom is such as to cause the axes of the said guide sprocket gears to shift in opposite directions.

5. In an excavating shovel, comprising, in combination, a body, a boom pivoted to said body, 5 means to raise and lower the boom, a dipper stick carrying excavating instrumentalities operatively connected with said boom, driving means on the swing body, driven means carried by the boom and engaging the dipper stick for operating the 10 same, a single flexible power transmission means interconnecting said driving and driven means and comprising an upper and a lower loop having angularly disposed left and right portions, and guide members rotative on said boom and beneath 15 which the respective upper and lower loops of the flexible transmission means are trained for guiding the flexible power transmission means, the centers of the rotative guide members being positioned with respect to the center of the boom 20 pivot in such a manner as to maintain the distances between a center line passing through the boom pivotal axis parallel to the left portions of the upper and lower loops of the flexible power transmitting means substantially equal at all 25 positions of working operation of the boom to thereby maintain the flexible power transmitting means taut.

6. In an excavating shovel, comprising, in combination, a body, a boom, a boom pivot connecting 30 the boom with said body, means to raise and lower the boom, a dipper stick carrying excavating instrumentalities operatively connected with said boom, driving means on the body, driven means carried by the boom and engaging the dipper 35 stick for operating the same, a single power transmission chain interconnecting said driving means and driven means, and a plurality of gears fixed to said boom and rotatable thereon for guiding said chain, said gears being positioned with the 40 lowest points of their pitch lines at substantially equal distances from said boom pivot so as to maintain the power transmission chain substantially taut under all operating positions of the boom.
